FEEDING MEANS FOR TICKET ISSUING MACHINES

Stanley Mark Dixon and Harold John Michael Gibbs, King's Cross, London, England, assignors to Westinghouse Garrard Ticket Machines Limited, London, England

Application April 11, 1950, Serial No. 155,153

Claims priority, application Great Britain May 3, 1949

2 Claims. (Cl. 271—2.4)

1

This invention relates to ticket issuing machines of the kind in which a strip of paper or thin card, upon which the information to be recorded upon each ticket is printed, is fed through the machine by being gripped between one or more pairs of rotatable rollers, termed transport rollers, any or all of which may be provided with type so that the information is printed on the strip as it is being fed through the machine, lengths of the printed strip corresponding to individual tickets being perforated or severed by an automatically operated knife of the guillotine type as it issues from the machine.

In such machines there is a space between the final pair of transport rollers and the knife, usually of sufficient length to accommodate one complete ticket. If the strip should be impeded as it issues from the machine, for example, by the hand of a purchaser of the ticket, the strip may buckle in the space between the final pair of transport rollers and the knife, with the result that the machine becomes jammed.

According to the invention in a machine of the above kind two parallel spaced superposed members are arranged to form a restricted passage between the final pair of transport rollers and the knife, at least one of the members having pivotally mounted at its end a finger which is biased to form between the rollers a flared entrance to the passage and which is rotated about its pivot by the entrance of the ticket strip into the passage so that the flared entrance is converted into a continuation of the passage.

By "restricted passage" is meant a passage of such dimensions that the strip is unable to buckle within it.

Preferably the end of the passage extending between the rollers is formed by one or more pairs of projecting fingers at least one of each pair projecting into a circumferential groove provided in the surface of one of the rollers, while the other of each pair is pivotally mounted in such a manner as to be rotated about its pivot by the entrance of the ticket strip into the passage whereby the flared entrance to the passage formed by each pair of fingers is converted into a continuation of said passage. Alternatively both of the fingers in each pair may be pivotally mounted on the parallel spaced superposed members.

The invention is illustrated by way of example in the accompanying drawings of which

Figure 1 is a part sectional view, in somewhat diagrammatic form, of the delivery mechanism of a ticket printing and issuing machine embody-

2

ing the invention, the section being taken along the line BB of Figure 2; and

Figure 2 is a view along the line AA of Figure 1.

Fig. 3 shows a portion of Fig. 2 on an enlarged scale.

Referring now to the drawings, a final pair of transport rollers 1, 2 are mounted vertically one above the other, the axes about which they rotate being horizontal and parallel with each other.

The upper roller 1, carries the necessary type wheels (not shown) mounted between a pair of side cheeks 3, 4 (Figure 2) provided with journals 5, 6, for rotatably supporting the roller in suitable bearings in brackets 7, 8. The lower roller 2 is mounted on journals 21, 22 which rotate in suitable bearings in brackets 7, 8. Mounted in fixed relation to the rollers 1, 2 are gears 23, 24 which are in constant mesh and through which the rollers are driven from a co-operating gear (not shown) in the machine. The roller 2 carries no type but has a portion 9 of enlarged diameter which, when the rollers are rotated, grips the ticket strip between itself and the type carried by roller 1, thus enabling information, such as the date, to be printed upon the strip while, at the same time, carrying the strip forward to the knife 10 which severs a ticket from the strip at the end of the operation.

Between the two rollers and the knife is a space sufficient in length to accommodate one complete ticket length of strip. Two brackets 11, 12 substantially L-shaped, are mounted in this space, each with one limb horizontal and parallel with each other and spaced apart vertically by a distance only slightly greater than the thickness of the strip, thus providing a kind of horizontal slot 13 which forms a restricted passage through which the strip is passed and in which its vertical movement is so restrained that it is prevented from buckling.

The length of horizontal limbs of the brackets is such that they extend from the knife to a position as close as is practicable to the rollers. In order to extend the restricted passage as far as possible into the space between the two rollers themselves, and thus to control the movement of the strip over as much as possible of the critical distance between the rollers and the knife, pairs of projecting fingers 14, 15 are mounted at the ends of the horizontal limbs of the brackets. The fingers 14 on the lower limb are fixed thereto and extend from it horizontally, their free ends being accommodated one in a circumferential groove 16 provided in the lower roller for that

purpose and the other between the roller 2 and the bracket 8. These ends are chamfered to assist in guiding the end of a newly fitted strip into the restricted passage.

The fingers 15 on the upper bracket are pivoted so as to be rotatable about a horizontal pivot 17. These fingers are pawl shaped and so mounted that, with the machine at rest and with no strip in the restricted passage, the "nose" of the "pawl" rests against a flat or cut away portion 18 of the upper roller 1 and is biased to this position by its own weight or by any other suitable method, for example, a spring. In this position the finger presents an inclined surface 19 to the end of an oncoming strip forming a flared opening to guide the end of the strip into the restricted passage. A corner 20 of the finger 15 projects into the restricted passage 13 in such a way that it is struck and lifted by the entering strip causing the finger 15 to rotate and bring the inclined surface horizontal, as in the position indicated by broken lines, thus forming, with the finger 14, a continuation of the restricted passage which accordingly then extends well into the space between the two rollers.

It is to be understood that both fingers may be pivotally mounted and function as described above.

The final pair of transport rollers may be made slightly less in length than the width of the strip, the fingers may then be mounted so that they extend either side of the rollers while still receiving the strip between them. This arrangement obviates the necessity for cutting a groove in either roller, or otherwise shaping them to receive the fingers.

Having thus described our invention, what we claim is:

1. In a ticket issuing machine an arrangement for feeding a ticket strip and preventing its buckling, comprising a final pair of transport rollers; a pair of parallel spaced superposed

members extending beyond said transport rollers and forming a restricted passage for the ticket strip; at least one finger pivotally mounted at the end of one of said members and biased so as to form a flared entrance to the passage; and on said finger a projection which is adapted to be moved by the entrance of the ticket strip into said passage to rotate the finger about its pivot so that the flared entrance is converted into a continuation of said passage.

2. In a ticket issuing machine an arrangement for feeding a ticket strip and preventing its buckling, comprising a first transport roller having a flat cut-away portion formed therein; a second transport roller cooperating with said first roller, when rotated, to feed the ticket strip; first and second parallel spaced superposed members extending beyond said first and second transport rollers and forming a restricted passage for the ticket strip; and pivotally mounted at the end of said first member a biased first finger having a first part resting against said flat cut-away portion of the first transport roller when said first transport roller is in a particular position, a second part forming a flared entrance to the passage, and a third part which is moved by the entrance of the ticket strip into said passage to rotate the finger about its pivot so that the flared entrance is converted into a continuation of said passage.
